(57) **CLAIM**

The ornamental design for a dual compartment container, as shown and described.

DESCRIPTION

FIG. 1 is a perspective view of a dual compartment container; FIG. 2 is a left-side elevational view thereof;

FIG. 3 is a right-side elevational view thereof;

FIG. 4 is a rear elevational view thereof;

FIG. 5 is a front elevational view thereof;

FIG. 6 is a top plan view thereof;

FIG. 7 is a bottom plan view thereof;

FIG. 8 is a top plan cross-sectional view thereof taken along line 8-8 of FIG. 13;

FIG. 9 is a bottom plan cross-sectional view thereof taken along line 9-9 of FIG. 14;

FIG. 10 is a top perspective cross-sectional view thereof taken along line 10-10 of FIG. 15;

FIG. 11 is a bottom perspective cross-sectional view thereof taken along line 11-11 of FIG. 16;

FIG. 12 is a bottom perspective view thereof;

FIG. 13 is a front elevational view thereof, showing the plane upon which a cross-sectional view is taken and shown in FIG. 8;

FIG. 14 is a front elevational view thereof, showing the plane upon which a cross-sectional view is taken and shown in FIG. 9;

FIG. 15 is a front elevational view thereof, showing the plane upon which a cross-sectional view is taken and shown in FIG. 10; and,

FIG. 16 is a front elevational view thereof, showing the plane upon which a cross-sectional view is taken and shown in FIG. 11.

The broken line showing of caps and a handle is for the purpose of illustrating environmental structure and forms no part of the claimed design.
